UNITED STATES PATENT OFFICE.

THEODORE EWOLDT, OF HOLSTEIN, AND JOHN A. HANSEN, OF KINGSLEY, IOWA.

SANITARY LAYING, SETTING, AND HATCHING NEST AND BROODING COOP.

Application filed May 22, 1924. Serial No. 715,119.

To all whom it may concern:

Be it known that we, THEODORE EWOLDT and JOHN A. HANSEN, citizens of the United States, and residents of Holstein and Kingsley, respectively, in the counties of Ida and Plymouth, respectively, and State of Iowa, have invented certain new and useful Improvements in Sanitary Laying, Setting, and Hatching Nests and Brooding Coops, 5 of which the following is a specification.

Our invention relates to a hen's nest adapted for use for laying and setting hens, and also adapted to use as a brooding coop for small chickens, and it is our object to 15 provide such a nest which is of simple, durable and inexpensive construction.

Another object is to provide in such a nest, a construction whereby the nest may be very readily cleaned and disinfected.

Another object is to provide a nest having a sloping rain-shedding roof or cover, the sides of the nest being so shaped and formed that the nests may be produced from a standard sheet of sheet metal without causing any waste.

A still further object is to provide a combination step or platform and closure for the entrance opening of the nest, together with means for securing the same in either 30 of two positions so as to serve either of the purposes.

Our invention preferably employs, in order to carry out the above objects, a construction wherein the body of the nest is 35 formed of four sides, open at the top and bottom and partly open at the front, a removable floor having a vertical front piece adapted to be secured to the sides by a sliding pin, so as to hold the floor in place, the 40 floor being supported upon an inturned bead formed on the lower edges of the sides, and a platform member hinged to the front piece and having a reinforcing rib or wire extended at its ends to form spring arms 45 adapted to engage the sides to hold the platform in either of its positions.

With these and other objects in view, our invention consists in the construction, arrangement and combination of the various 50 parts of our device, whereby the objects contemplated are attained, as hereinafter more fully set forth, pointed out in our claims and illustrated in the accompanying drawings, in which:

Fig. 1 is a perspective view of our nest,

the removable floor being shown partly removed in light dotted lines, and the platform being shown serving as a closure, in heavy dotted lines.

Fig. 2 is a detail sectional view of the 60 same.

Fig. 3 is a detail sectional view, taken on the line 3—3 of Fig. 4.

Fig. 4 is a detail view illustrating the 65 platform hinge from the inside of the nest.

Fig. 5 is a plan view of a piece of sheet metal, cut so as to form substantially all 70 of the parts for two nests.

Fig. 6 is an elevation of a portion of the 75 front of the nest, and

Fig. 7 is a side view of a portion of the 80 nest with the parts in an adjusted position.

The four sides of our improved nest may be formed either from a continuous strip, A, or a strip, B, as illustrated in Fig. 5. The 75 sides, 10, are cut on a slant at their upper edges, and the strip is bent so as to form the sides, 10, the front, 11, and the back, 12, as indicated by the dotted lines, 13, in Fig. 5. It will be seen that by cutting the sheet of 80 metal so that in the strip, A, the front, 11, is at the end of the strip, and in the strip, B, the back, 12, is at the end, the strip may be entirely used. The front is cut away so as to leave the opening, 14, when the sides are 85 bent into assembled position, and the portion thus cut away may be utilized in making the step member which will be referred to hereinafter.

The upper edges of the sides, front and 90 back, are rolled around the reinforcing wire, 15, which at the upper corners is looped to provide the eyes, 16, from which the nest may be supported.

The cover or roof, 17, is hinged to the 95 back, 12, by means of the loops, 18, which receive the wire, 15. The cover is provided with down-turned flanges, 19, the front flange being provided with a lip, 20, which coacts with a spring latch clip, 21, fixed to 100 the front, 11.

The lower edges of the sides and back are rolled around the reinforcing wire, 22, which extends across the open space in front of the nest. The removable bottom, 23, 105 rests upon the lower beaded edges of the sides and back of the nest, and also upon the portion of the wire, 22, extending across the front of the nest.

The bottom, 23, is provided with the up- 110

wardly-extending front piece, 25, which at its top is rolled to form a tubular sleeve portion, 26. Openings, 27, are provided in the sides, 10, adapted to register with 5 the portion, 26, when the floor is in closed position, and a locking pin, 28, is provided which, when extended through the openings, 27, and tubular portion, 26, serves to lock the bottom in place and at the same 10 time to brace the front portion. It will be seen that the front piece, 25, being positioned between the sides, 10, braces them against inward movement.

The platform, 29, is provided, with the 15 hinge loops, 30, extended through slots, 31, in the piece, 25, and there secured by cotter pins, 32, or the like.

The metal of the platform, 29, at its edges is rolled around the frame wire, 33, which 20 is preferably of spring steel. The ends of the wire are extended and bent, as at 34, so as to reach the lower edges of the sides, 10, at a point spaced inwardly from the front, when the platform is in the raised 25 position shown in heavy dotted lines in Fig. 1, and on the ends of the wire are provided the hooked portions, 35, which engage the under edges of the sides, when the platform is raised. When the platform is 30 in the position shown in full lines, the hooks, 35, are received in the openings, 36, and the platform is thus braced in such position.

The front piece, 25, may be provided with 35 a longitudinal opening, 37, as shown in Fig. 6, which is closed by a sliding door, 38.

We provide the openings, 39, the purpose of which will be hereinafter disclosed.

The sides, 10, may be provided with openings, 40, for ventilating purposes.

In the practical use of our nest, for laying it may be hung on suitably located 45 nails or screws spaced to receive the loops, 16. The platform, 29, is adjusted to the horizontal position shown in Fig. 1, and the cover closed down. For the ordinary hen the opening, 14, provides sufficient entrance-way, but the nest may also be utilized for larger hens, such as plymouth rocks, by 50 lifting the cover, 17.

The hen is provided with a closed nest where she is substantially protected from disturbance from others, the restricted 55 opening, 14, serving to prevent ready access of a second hen, and better laying is promoted in this way.

The entrance, 14, being narrow, would 60 make it difficult for the hen to obtain access to the nest in the absence of the platform, 29. With this construction the hen can fly up to the platform, 29, and then very readily enter the nest through the restricted opening.

When it is desired to move the nest, it 65 is simply lifted from its supporting pegs

and may then be transferred to any new location, or disassembled for cleaning or disinfecting.

It is well known that the ordinary nest provides a ready breeding place for lice and mites, and it is therefore highly important that the nest be cleaned regularly.

Our nest is especially adapted to this purpose. It is only necessary to remove the nest, draw out the pin, 28, and slide out the 75 bottom, 23, as indicated in dotted lines in Fig. 1. The nesting material and offal is then readily dumped into a refuse pile, the bottom may be scraped, if necessary, and all 80 of the parts dipped in a cleaning and disinfecting or insecticidal solution. The nest may be cleaned while supported on the wall of the chicken house, if desired, by removing the bottom, raising the cover and pouring the proper solution through the shell. 85

When used for setting purposes, the hen may be confined by raising the platform, 29, so as to close the opening, 14. The arms, 34, are of spring material so as to allow withdrawal of the hooks, 35, from the openings, 36, and to urge them under the edges 90 of the sides, 10, for holding the platform in such position.

When used as a brooder, the door, 38, may be partly opened in order to allow the little chicks to pass in and out, and the platform raised, if necessary or desirable, to keep the hen imprisoned. The door, 38, may be dispensed with in one form of our invention, and its purpose achieved by sliding the floor forwardly a distance sufficient 100 to leave apertures between the ends of the front piece, 25, and the sides, 10. In this position the floor may be locked by inserting the hooks in the openings, 39. The position is shown in Fig. 7. It will be seen that the platform is maintained in vertical position so as to prevent escape of the hen.

Some changes may be made in the construction and arrangement of the parts of 110 our invention without departing from the real spirit and purpose of our invention, and it is our intention to cover by our claims any modified forms of structure or use of mechanical equivalents which may be reasonably included within their scope. 115

We claim as our invention:

1. A hen's nest comprising a body portion having sides, back, and partly open front, a bottom having a front piece adapted to partly close the front, a platform hinged to said front piece, and resilient arms secured thereto and embracing the sides, said arms being provided with means to engage the sides in various positions, the platform being positioned to swing from horizontal position to vertical position for closing the opening in the front. 120

2. A hen's nest comprising a body portion having sides, back, and partly open front, 125

a reinforcing, inwardly-extending flange on the lower edges of the sides and back, a removable bottom supported on said flange, having a front piece adapted to partly close the front, a platform hinged to said front piece, and resilient arms secured thereto and embracing the sides, said arms being provided with means to engage the sides, in various positions, the platform being positioned 10 to swing from horizontal position to vertical position for closing the opening in the front.

3. A hen's nest comprising a body portion having sides, back and partly open front, a removable bottom having a front piece adapted to partly close the front, a sleeve on the upper edge of the front piece, the sides being provided with openings registering with said sleeve, and a locking pin received 20 through said sleeve and openings, a platform hinged to said front piece, and resilient arms secured thereto and embracing the sides, said arms being provided with means to engage the sides in various positions, the platform being positioned to swing from horizontal position to vertical position for closing the opening in the front.

4. A hen's nest comprising a body portion having sides, back and partly open front, a reinforcing wire fixed to the upper edges of the sides, front and back, said wire being looped at the rear corners of the nest to provide supporting means, a bottom having a front piece adapted to partly close the front,

a platform hinged to said front piece, and 35 resilient arms secured thereto and embracing the sides, said arms being provided with means to engage the sides in various positions, the platform being positioned to swing from horizontal position to vertical position 40 for closing the opening in the front.

5. A hen's nest comprising a body portion having sides, back and partly open front, a bottom having a front piece adapted to partly close the front, a sliding door in said 45 front piece, a platform hinged to said front piece, and resilient arms secured thereto and embracing the sides, said arms being provided with means to engage the sides in various positions, the platform being positioned to 50 swing from horizontal position to vertical position for closing the opening in the front.

6. A hen's nest comprising a body portion having sides, back and partly open front, a removable bottom having a front 55 piece adapted to partly close the front, a sleeve on the upper edge of the front piece, a locking pin designed to be received in the sleeve and registering openings in the sides, and a platform hinged to the front piece 60 adapted for adjustment to horizontal position or vertical position serving as a closure.

Signed at Kingsley, in the county of Plymouth, and State of Iowa this 13 day of May, 1924.

THEODORE EWOLDT.
JOHN A. HANSEN.
